UNITED STATES PATENT OFFICE

2,403,137

BASING FOR ELECTRIC LAMPS AND THE LIKE

Royal F. Strickland, Cleveland Heights, Ohio, as-
signor to General Electric Company, a corpo-
ration of New York

Application July 1, 1943, Serial No. 492,988

2 Claims. (Cl. 176—32)

1

This invention relates to basing the bulbs or envelopes of electrical devices, including incandescent lamps as well as discharge devices of various kinds, which at present generally have vitreous envelopes. The invention aims at simplifying the attachment of the base to the electrical device or bulb, and at lowering the cost. In suitable forms of embodiment, the invention allows of dispensing with the basing machinery now commonly used in basing electric lamps; of doing away with basing cement such as is used to provide a mechanical attachment of the bases to the lamp bulbs; of dispensing with soldering, welding, or other such methods of making electrical connections between lamp leads and lamp base contact terminals; and of making the base contacts of any metallic materials that are electrically, mechanically, and commercially most suitable—such as aluminum, for example—without regard to their adaptation for soldering or welding. Other features and advantages of the invention will become apparent from the description of species and forms of embodiment, and from the drawing.

In the forms of construction here illustrated, the main attachment of the base to the lamp bulb is made by direct mechanical engagement of a base shell with a lamp bulb, by screwing the shell directly on the bulb end or neck, without any need of basing cement. This makes the construction very advantageous for bases of Edison or screw types—though it is also applicable to other types of bases having shells that are internally screw threaded, even though they might be externally plain and unthreaded. With the screw connection is combined an adhesive attachment of the base contact shell to the bulb neck, by a film of suitable adhesive applied between their inter-engaging surfaces, to secure the contact shell against unscrewing from the neck when the device is unscrewed from a socket in external screw engagement with the shell. Since the screw shell can be screwed on and finally jammed on the bulb neck with more force than need ever be used in screwing the lamp into a socket, and since the torque required to unscrew a lamp from a socket is much less than that used in screwing the lamp into the socket, the unscrewing torque to be taken by the cement is quite moderate, and well within the holding power of a good cement. The bulb threads may be of incomplete or mutilated character, although simple, ordinary threads are at present generally preferred. The electrical connections of the lamp leads to the base con-

2
tacts are made without solder, by mere mechanical clamping.

In one form of construction, the "side" lead to the screw shell contact is wedged or crowded between the outside of the bulb neck and the inside of the shell, and thus held clamped into electrical contact with the shell. To reduce the resulting eccentric pressure and stress affecting the bulb neck, the neck may have a longitudinal depression or groove across its screw threads to accommodate the side lead. However, such grooving across the threads is not always essential.

In the drawing, Fig. 1 is a side view of a lamp bulb suitable for the purposes of the invention; Fig. 2 is a similar but tilted view of a base for this lamp, part of the screw shell being broken out to reveal its interior; and Fig. 3 is a fragmentary tilted view, partly sectional, showing the application of the base to the lamp.

Fig. 4 is a fragmentary side view illustrating a modified construction, the base being shown in section and the lamp bulb neck to which it is applied in elevation; Fig. 5 is a similar view illustrating another modification; and Fig. 6 is an "exploded" tilted view of the parts of the base shown in Fig. 5.

Fig. 1 shows an ordinary type of electric lamp L whose bulb end or neck 10 is externally screw threaded at 11 in a manner suitable for the purposes of my invention. As illustrated, the end of the bulb neck 10 is closed, and the construction is of an ordinary type comprising a stem flare 12 fused and sealed to the neck at 13 and itself closed at its inner end by a pressed seal 14 through which are sealed the current lead wires 15, 16 to the electric translation means of the device, such as an incandescent coiled coil tungsten filament 17 suitably mounted in the bulb 10. An exhaust tube 18 is shown as opening through the seal or press 15, and is itself sealed or tipped off at its outer end after the usual exhaust-processing, such as evacuation and gas charging (if the lamp is of gas-filled type). The screw-threads 12 may be formed or molded in the bulb neck 11 in any suitable or preferred manner; for example, they may be formed just after "sealing in," by placing the bulb neck (while still hot and soft) in a mold of suitable internal conformation and blowing air into the bulb through the tube 18. This, of course, is done before the bulb is exhaust-processed and tipped off.

As thus far described, the bulb or envelope L and its threaded portion 11 do not differ greatly from what is disclosed in such U. S. patents as

3

No. 1,650,289 to McGinley and No. 2,066,317 to Blake and Geiger—though the described method of forming the threaded part 11 is different from those set forth in these patents.

Fig. 2 shows one form of lamp base B that is suitable for the purposes of my invention, being an Edison screw base comprising a sheet metal screw contact shell or skirt 20 with an insulative body, web, or button 21 (such as glass) at one end thereof. As in present commercial screw bases, the shell 20 may consist of a section of substantially cylindrical thin-walled tubing having a few turns of rounded screw-thread 22 rolled into its mid-portion, and having one end flared outward in a rounded bead 23, while its other end is flanged and rounded inward at 24 and molded into the glass (or other thermoplastic material) forming the base-end 21. The end-body or insulator 21 is shown as of frustroconical conformation where it projects from the corresponding end of the screw-shell 20. On the outer side of the insulative body 21 is exposed an end or center contact 25, here shown as a sheet metal disc forming the enlarged outer head or flange of a rivet-like center contact eyelet whose hollow shank or sleeve portion 26 is molded into the body 21 and is open through it, just as in ordinary commercial Edison bases.

Unlike the center contacts of ordinary commercial bases, the contact disc or flange 25 has a notch or slit 27 extending inward from its periphery to or even into the flaring end of the sleeve 26, and the margin of the sheet metal at one (counterclockwise) side of the slit 27 is raised or turned up at 28, above that at the other side of the slit, over an angular width of a few degrees (counterclockwise) around the disc. The slotted feature of the center contact 25, and its use as hereinafter described in electrically connecting the center lead 16 to this contact—these correspond essentially to what is disclosed in the application of John J. Malloy, Serial No. 447,818, filed June 20, 1942, now Patent No. 2,336,556, assigned to the assignee of this application.

Before applying the base B to the lamp L, the lamp lead 15 which is to be the "side" lead to the screw shell 20 is bent outward across the sealed neck end 13 and back lengthwise of the neck 10, to extend crosswise of the screw threads 11 and even somewhat beyond them. The lamp lead 16 which is to be the "center" lead to the end contact 25 may be left extending straight outward from the neck end 13. As shown in Fig. 1, the bulb neck 10 has a longitudinal channel or groove 30 extending from the beginning of the threads 11 outside the seal 13 across the threaded zone and even slightly beyond, to accommodate the side lead 15 when retroverted as above mentioned. The essential features of this groove appear best in Fig. 3, which shows the base B installed on the lamp bulb L. While the groove 30 is not here shown as of uniform depth below the undulatory general surface of the glass across the threaded area, its bottom, nevertheless, has undulations corresponding with those of the general surface, though of much smaller amplitude: i. e., the groove 30 cuts almost if not quite through the full depth of the protuberant thread ridges, but is only slightly sunk into the bottoms of the thread valleys at 31. If the groove depth at 31 is less than the diameter of the lead wire 15, the wire would obviously be crowded against the internal ridges of the screw shell threads; but even with the groove depth at

31 exceeding the wire diameter, as shown in Fig. 3, the wire is nevertheless clamped, effectively, against the shell 20 into electrical contact therewith, being touched and resiliently flexed slightly by the internal shell thread ridges, since at the glass-thread ridges the groove bottom lies further from the common axis of bulb neck and screw shell than do the crests of the internal shell-thread ridges. In other words, the condition of the wire 15 in the groove 30 resembles that of a beam continuous across a series of supports and loaded at the center of each span with concentrated loads not exceeding its elastic limit.

Thus the groove 30 differs very essentially from the superficially similar groove in the above-cited McGinley patent, which is everywhere so deep that McGinley's side-lead lies sheltered in its bottom, without being in any wise forced into contact with the screw shell—to which, indeed, it is electrically connected by solder at the edge of the shell.

When the base B is to be put on the lamp bulb L, a few drops of adhesive of any suitable character are first applied to the inside of the screw shell 20, as indicated by the shaded area 33 in Fig. 2, or to the bulb neck portion 12 as indicated by the shaded area 34 in Fig. 1, or both. Then the center lead 16 is threaded through the end contact hole or bore in the eyelet shank 26 and the base B is screwed on the bulb neck 10 while the side lead 15 is held in place in the neck groove 30 by its end that projects beyond the screw threads 11 as shown in Fig. 1. Screwing on the base B in this manner not only squeezes and spreads the adhesive 33 or 34 into a thin film between the threaded surfaces of the parts 11 and 20, but also forces and clamps the lead wire 15 into electrical contact with the inside of the screw shell 20. Any adhesive on the shell 20 where the wire 15 bears against it is scraped away by the wire—or squeezed out from between the parts by the pressure—insuring good contact. The free end of the wire 15 may then be cut off flush with the shell edge 23. After the base B has been screwed home firm and tight on the bulb neck—so tight, even, that it can scarcely be unscrewed by hand—the lead wire 16 is bent aside and engaged in the slit 21 of the disc 25 and then bent on around the shank 26 and crowded under the disc, lifting the disc margin from the base end 21 and clamping the wire under the disc. By subsequently forcing or flattening down the raised margin of the disc 25 outside the wire 16 all the way around—after cutting off the free wire beyond the disc edge and pushing the wire end in under the disc—the wire 16 is clamped still more firmly and secured against outward displacement. This final condition of the parts is shown in Fig. 3. When the film of adhesive between the shell 20 and the neck portion 12 has dried or hardened, it secures the shell against unscrewing from the neck when the lamp L is unscrewed or backed out of the screw shell contact of a socket (not shown) into which it has been screwed in service.

shown) into which it has been 65 applied to the screw shell at 33 or to the bulb neck at 34 may be of any kind that will form a thin film and will when dry, hard, or "cured" bond the parts together against unscrewing from one another in service. For example, it may be of a varnish type, comprising a base of rubber, gum, resin, or asphaltum, etc., in a suitable volatile solvent—such as shellac in alcohol—or it may be of a water-glass type, consisting of a soluble silicate—as of sodium, potassium, or zirconium—dissolved in water. Slow- 70 75

setting gums or plastics are also suitable, since it matters very little how long it takes the adhesive to harden after the screw shell is screwed on the bulb neck.

The construction illustrated in Fig. 4 differs from that of Figs. 1-3 both as regards the connections of the leads 15, 16 to the shell and center contacts and also as regards the attachment of the insulative base end 21a to the screw shell 20a—corresponding in this latter respect substantially to what is disclosed in U. S. Patent 2,210,525 to Carl A. Brown and Clarence E. Hahn. Accordingly, the insulative base end 21a is shown as a bevelled button (preferably glass) that is centrally apertured at 26a for passage of the center lead-wire 16 and is peripherally engaged and seated in and against an annular seat 35 formed at the outer end of the shell 20 by doubling the sheet metal of the shell back thereinto and flanging its extreme margin inward. The button 21a may be peripherally gripped and secured in the seat 35 by spinning in the outer annular corner of the seat on the bevelled button edge, as shown at 36. The side lead 15 is not retroverted as in Figs. 1 and 3, but extends from the neck end 13 to the shell-end seat 35, where it bends outward under the button 21a and then across its outer edge as shown, being thus held clamped into electrical contact with this shell portion 35 by the grip of the annular corner or margin 36 of the seat 35 on the button. The end contact 25a is shown as a mere cap whose annular wall (which may be crimped as shown) is wedged fast and thus clamped in a corresponding annular groove 37 in the outer side of the insulator 21a concentric with the lead hole 26a, as shown in U. S. Patents 2,047,043, granted to me July 7, 1936, and 2,066,317, granted to Blake and Geiger January 5, 1937—the latter already hereinbefore mentioned. The center lead 16 is shown as secured and electrically connected to the end contact 25a by being clamped between the insulator 21a and the interior surfaces of the contact cap 25a as in the two patents last cited. The side lead 15 not being retroverted between the screw shell 20a and the bulb neck portion 12, the groove 30 of Figs. 1 and 3 is entirely superfluous, and is omitted in Fig. 4.

The construction illustrated in Fig. 5 differs from that of Fig. 4 in having its insulative base end or button 21b secured in the screw shell seat 35b by snap action; in having its center contact 25b also snap-fastened to the insulator 21b; and in having the leads 15, 16 clamped into electrical contact with the shell and center contacts 20b, 25b by the elastic action of the snap fastenings—all as shown in U. S. application Serial No. 456,351, filed August 27, 1942, by Paul O. Cartum, now Patent No. 2,336,529.

As in Figs. 11 and 12 of the said Cartum application, the plain annular wall of the insulator seat 35b is interrupted by the punching out of a few isolated spring fingers 37 (three being shown) whose free lower ends are bent inward to snap into corresponding bevel-shouldered notches 38 in the insulator 21b when the latter is put in place and pushed home in the seat 35b. As in Figs. 1, 2, and 3 of said application, the center contact 25b consists of a disc-like head with a hollow shank that engages in and around a corresponding central recess or hole 39 in the insulator 21b, the internal wall of this opening 39 being bevelled inward from the flat outer end surface of the insulator. The shank of the center contact 25b is slit into a number of spring locking fingers 40

which are shown with external bevelled shoulders at their free lower ends, for snapping outward behind the shoulder of the opening 39 when the contact is pushed home into the opening. The contact 25b may be formed of sheet metal by a die-pressing and drawing operation, the margin of its head being formed by doubling under the sheet metal as shown in Fig. 5.

The connection of the side lead 15 to the screw shell 20b may be made by simply passing the lead through the shell 20b when the base B is put on the bulb neck, and then bending the lead 15 aside so that it will be clamped between the shell portion 35b and the insulator 21b, when the latter is snapped into place, by the elastic snap action of the resilient fingers 37. Afterward, the wire 15 may be cut off about as shown at 42. The connection of the center lead 16 to the contact 25 may be made in a similar way, by passing this lead through the insulator opening 39 when the base B is put on the bulb neck and bending the lead aside, so that it will be clamped between the contact 25b and the flat outer surface of the insulator 21b when contact is snapped into place, by the elastic snap action of the spring fingers 40. Afterward, the wire 16 may be cut off as indicated at 43.

It will be appreciated that the constructions shown are extremely simple and easy to assemble, and are composed of parts that are likewise simple, rugged, and economical to manufacture. The metal parts 20, 20a, 20b and 25, 25a, 25b may advantageously be made of brass, iron or mild steel, or of aluminum, while the insulative parts 21, 21a, 21b may be of glass, indurated fiber, or molded plastic. The lead-wires 15, 16 may likewise be of any metals otherwise most suitable, since they do not have to be soldered or welded to the parts 21 or 25, etc.

In Figs. 4, 5, and 6, various parts and features are marked with the same reference characters as those corresponding in earlier figures, in order to dispense with repetitive description—a distinctive letter being added where such distinction seems desirable.

What I claim as new and desire to secure by Letters Patent of the United States is:

1. The combination with a vitreous lamp bulb or the like having an externally screw threaded neck, with current leads issuing therefrom, and also having across the screw threads a groove with its bottom undulated in correspondence with the undulations of the screw threaded neck surface, but to a less depth, of a metal screw shell contact screwed on said threaded neck, with an adhesive film between said neck and shell securing the latter against unscrewing from the neck when the device is unscrewed from a socket in external screw engagement with said shell, one of said current leads extending along in said neck groove resiliently flexed between the undulations of the groove bottom and the internal undulations of said screw shell, and thus held in electrical contact with the latter; a base end insulator closing the end of said shell; and an end contact mounted on said insulator having another of said current leads mechanically clamped into electrical contact therewith.

2. The combination with a vitreous lamp bulb or the like having an externally screw threaded neck, with current leads issuing therefrom, and also having across the screw threads a groove with its bottom undulated in correspondence with the undulations of the screw threaded neck surface, but to a less depth, of a metal screw shell

contact screwed on said threaded neck, with an adhesive film between said neck and shell securing the latter against unscrewing from the neck when the device is unscrewed from a socket in external screw engagement with said shell, one of said current leads extending along in said neck groove resiliently flexed between the undulations

of the groove bottom and the internal undulations of said screw shell, and thus held in electrical contact with the latter; a base end insulator closing the end of said shell; and an end contact on said insulator having another of said current leads electrically connected thereto.

ROYAL F. STRICKLAND.
